H. L. LIPMAN.
SELF FEEDING EYELET MACHINE.

No. 11,260.

Patented July 11, 1854.

UNITED STATES PATENT OFFICE.

HYMEN L. LIPMAN, OF PHILADELPHIA, PENNSYLVANIA.

EYELET-MACHINE.

Specification of Letters Patent No. 11,260, dated July 11, 1854.

To all whom it may concern:

Be it known that I, HYMEN L. LIPMAN, of the city and county of Philadelphia and State of Pennsylvania, have invented certain new and useful Improvements in Eyelet-Machines; and I do hereby declare the following to be a full, clear, and exact description thereof, reference being had to the accompanying drawing, making a part of this specification, and which represents a perspective view of the entire machine.

The nature of my invention relates to the combining with the fastening apparatus of an eyelet machine, a self feeder, which will carry the eyelets from a reservoir underneath the fastener.

To enable others skilled in the art to make and use my invention, I will proceed to describe the same with reference to the drawing.

The stock A, may be cast in one piece, of any suitable form of material, and is provided with a punch B, and fastener C, both of which may be operated by a double acting lever D, the one rising as the other is forced down. The shanks of the punch and fastener are surrounded with helical springs, so as to keep their tops in contact with the lever D, and each are respectively furnished with their counter dies or anvils b, c.

On the table E, or on the stock itself, may be arranged the ways F, in which slides or moves a forked carrying arm G, to which is attached a cord a, and weight H, for drawing it back, its forward motion being achieved by means hereafter described.

A reservoir or receptacle I, for holding the eyelets attached to the machine and supported by the arm J. A stem or wire d, on which the eyelets are threaded passes through the center of said reservoir, and as the eyelets are successively carried forward to the fastener C, they descend along said rod or wire d so that at one eyelet is always ready to be caught between the jaws e e of the carrying arm G, and transferred under the fastener.

The eyelets f on the stem (a portion of the tube or reservoir being broken away to show their position) set one within the other, this being due to their form, and it is obvious that a mere pushing arm would not separate them. To meet this difficulty the jaws e, e, have inclined planes on their upper sides, so that while they catch the lower eyelet, they

at the same time raise up the balance of the column of eyelets, so as to release the under one. The bottom of the tube is just near enough to the slide to allow the slide to move, but prevent the eyelets from dropping out. 60

A lever arm K, is connected with the lever D, so as to be operated by it, and to this lever arm is connected a cord g, which is fastened to an eye h, on the slide G. When the lever D, is thrown to the left it draws the slide forward under the fastener with its eyelet, and when the lever is swung the other way the weight H, draws back the slide, it having left the eyelet directly under the fastener. The paper, leather or whatever is be 70 furnished with the eyelets is placed with the hole previously punched in it over the eyelet, the lever brought down, and the material is forced over the eyelet, and the flange turned over on top of the eyelet, and 75 the whole secured.

Now it is obvious that modifications of this machine may be made without in the least changing its character or principle. A spring may be used instead of the weight, 80 the lever D, may be of different form, and operated by foot treadles from below, or by a yoke on top. The punching may also be done by a separate machine if found essential, and adjustments and stops be added, for 85 making the machine very exact in all its movements. All these will suggest themselves to any skillful mechanic without requiring invention, and I desire to protect my invention against the mere changes of parts, 90 that will accomplish the same results, by substantially the same means.

Having thus fully described the nature of my invention and shown how the same may be practically applied, what I claim as 95 new, and desire to secure by Letters Patent, is—

1. In combination with a fastener C, and a reservoir of eyelets I, the conveying apparatus for carrying the eyelet from one to 100 the other, made and operated substantially in the manner herein described.

2. I also claim the threading of the eyelets upon a rod or stem from which they may be delivered one at a time to the carrying apparatus substantially as described. 105

HYMEN L. LIPMAN.
